Primary Examiner — Mimosa De*(74) Attorney, Agent, or Firm* — Georgi Korobanov(57) **CLAIM**

The ornamental design for a chair, as shown and described.

DESCRIPTION

FIG. 1 is a perspective view of a chair showing my new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of portion of FIG. 1; and,

FIG. 9 is an enlarged view of portion of FIG. 2.

The broken lines are shown for the purpose of illustrating portions of the chair and forms no part of the claimed design.

1 Claim, 9 Drawing Sheets(56)
